UNITED STATES PATENT OFFICE.

ROBERT B. TUNSTALL, OF NORFOLK, VIRGINIA.

DESIGN FOR HEAD OF PICTURE-SCREWS.

SPECIFICATION forming part of Design No. 12,074, dated December 21, 1880.

Application filed September 25, 1880. Term of patent 7 years.

To all whom it may concern:

Be it known that I, ROBERT B. TUNSTALL, a citizen of the United States, residing at Norfolk, in the county of Norfolk and State of Virginia, have invented and produced a new and original Design for the Heads of Picture-Screws, of which the following is a specification, reference being had to the accompanying drawings, forming part thereof.

Figure 1 is a plan view of my newly-designed head of picture-screws, and Fig. 2 is a central vertical section of the same. Fig. 3 simply illustrates the screw-shank of a picture-screw upon which the head, as shown in Figs. 1 and 2, is adapted to be screwed for use for sustaining picture-frames.

Heretofore, ordinarily, the surface of the head of a picture-screw, which when in use is mostly exposed to the eye of the observer, has been made in convex form. This surface of the head of a picture-screw I ornament by the design shown in plan view in Fig. 1, such ornamentation being impressed upon or in or painted upon the metal of which the head is com-

posed, and the design of my ornamentation 25 may be presented to the eye of the observer in a color which is either that of gilt, or of bronze, or of nickel, or in any of the colors or combinations of colors which can be represented by paint.

My design for ornamenting the heads of picture-screws consists of a central circular ornamental portion, as at A, surrounded by a series of leaves projecting therefrom, as at b, an intermediate series of leaves, as at c, and 35 a backing or base series of leaves, c', as shown, the same being all contained within the perimeter of the head, and together forming my design for ornamenting the head of a picture-screw.

I claim—

The ornamental design for the head of a picture-screw, substantially as described.

ROBT. B. TUNSTALL.
